United States Patent Office

Des. 216,467
Patented Jan. 13, 1970

216,467

ENCLOSURE FOR DIGITAL VOLTMETER OR THE LIKE

Paul E. Brefka, Framingham, Mass., assignor, by mesne assignments, to Tyco Instrument Division, Inc., Waltham, Mass.

Filed Aug. 27, 1968, Ser. No. 13,290

Term of patent 14 years

Int. Cl. D14—02

U.S. Cl. D26—5

FIG. 1.

FIG. 2.

FIG. 1 is a front perspective view of the enclosure for digital voltmeter; and

FIG. 2 is a rear perspective view.

The essential features of the design reside in the portions shown in full lines.

I claim:

The ornamental design for an enclosure for digital voltmeter or the like, substantially as shown and described.
